UNITED STATES PATENT OFFICE.

ROSS MORRIS, OF CLARKSBURG, WEST VIRGINIA, ASSIGNOR OF ONE-HALF
TO ALFRED A. SCOTT, OF SAME PLACE.

DESIGN FOR A MEDICATED AIR-HEAD.

SPECIFICATION forming part of Design No. 29,140, dated August 2, 1898.

Application filed June 27, 1898. Serial No. 684,626. Term of patent 14 years.

To all whom it may concern:

Be it known that I, Ross MORRIS, a citizen of the United States, residing at Clarksburg, in the county of Harrison and State of West Virginia, have invented and produced a new and original Design for Medicated Air-Heads for Delivering Medicated Vapors and the Like from Atomizers, Vaporizers, &c., of which the following is a specification, reference being had to the accompanying drawings, forming part thereof, and in which—

Figure 1 is a perspective view of a medicated air-head, showing my new design. Fig. 2 is a side view, and Fig. 3 is a cross-sectional view on about line 3 3 of Fig. 2.

The leading or material feature consists of the design forming the subject of the accompanying illustration.

In such illustration the body A is shown as octagonal in cross-section, with the panels a,

and is sloped inward at B below said panels a and has the plane inwardly-inclined surfaces C above said panels, from one of which extends the curved projection E and from the apex or crown of which extend the parallel projections D D, arranged in lines on opposite sides of the line of the projection E. The projection E extends upward and outward from the body A on a curved line, as clearly shown.

Having described my invention, what I claim as new, and desire to secure by Letters Patent, is—

The design for a medicated air-head, as herein shown and described.

ROSS MORRIS.
